UNITED STATES PATENT OFFICE.

JAMES DALTON, OF LOS ANGELES, AND BERNARD C. DE MEULLE, OF LONG BEACH, CALIFORNIA, ASSIGNORS TO DALTON OVEN CO., A COPARTNERSHIP COMPOSED OF JAMES DALTON AND BERNARD C. DE MEULLE, OF LONG BEACH, CALIFORNIA.

REEL-OVEN.

1,399,750.

Specification of Letters Patent. Patented Dec. 13, 1921.

Application filed June 4, 1919. Serial No. 301,805.

To all whom it may concern:

Be it known that we, JAMES DALTON, a citizen of the United States, and BERNARD C. DE MEULLE, a subject of the King of Great Britain, the former residing at Los Angeles, in the county of Los Angeles and State of California, and the latter residing at Long Beach, in the county of Los Angeles and State of California, have invented a new and useful Reel-Oven, of which the following is a specification.

Our invention relates to bakers' ovens, being more particularly of the type known as reel ovens. One of the great objections on the part of operators of reel ovens to the use of such an oven is that when opening the door to load or unload the oven the heat from the oven rushes out of the door to such an extent that in some cases the operator is singed and burned, and always during such operations the heat is so great that such operations are extremely unpleasant. This action of the heat rushing outwardly through the door is partly due to the fact that the oven door is usually placed well up on the side of the oven, and one of the principal objects of our invention is to provide a construction whereby the heat from the oven is sucked upwardly directly over the door opening thereby preventing the blast of heat through the open door.

Another object of our invention is to provide a radiation plate over the combustion chamber so arranged as to diffuse the heat from the combustion chamber more evenly throughout the baking chamber.

A further object of our invention is to provide means whereby the oven may be manually operated in case the power should fail, and also during the loading or unloading operation.

Further objects and advantages will be made evident hereinafter from the following specification.

Referring to the drawings, which are for illustrative purposes only,

Figure 1 is a vertical sectional view of an oven embodying a form of our invention.

Fig. 2 is a vertical sectional view through half of the upper portion of the oven.

Fig. 3 is an enlarged vertical sectional view of the oven door and its adjacent parts.

Fig. 4 is a diagrammatic, vertical, longitudinal sectional view of the oven, and

Fig. 5 is a diagrammatic view showing the driving mechanism for the oven.

The oven consists of lower sections 11, intermediate sections 12, and a roof section 13, the lower sections 11 resting upon walls 14 of the combustion chamber 15. The combustion chamber 15 is provided with a door 16 and with a hearth 17 above which is arranged a gas burner 18 or other suitable means for producing combustion. Forming the upper portion of the combustion chamber is a curved plate 20, hinged at 21 to one of the walls 14 and having its opposite edge 22 resting upon a latch 23 whereby the plate 20 is held in place, the latch 23 being pivotally mounted in one of the walls 14 as indicated at 24 and having a handle 25 whereby the latch may be readily operated to release the plate and permit the same to swing downwardly into the combustion chamber as hereinafter referred to. A portion of the plate 20 at each side is cut away as indicated at 26 to permit the hot products of combustion to pass from the combustion chamber to the baking chamber.

In the form shown the lower sections 11 of the oven are angularly disposed and are connected at their upper ends in any suitable manner to the intermediate sections which are vertically disposed, the upper ends of the intermediate sections being connected in any suitable manner to the roof section which, in cross-section, is shown in Fig. 1 in the form of a semicircular arch. Each of the sections 11, 12 and 13 is formed with an outer sheet metal wall 30 and an inner sheet metal wall 31, the inner wall 31 being covered on the outside by a layer of asbestos 32 or other heat insulating material, an air space 33 being left between the asbestos and the outer sheet metal 30. The end walls 34 are vertically arranged and close the ends of the oven.

Mounted upon a shaft 35 which extends through the end walls of the oven, being suitably journaled therein, is a reel of any

common form and construction indicated at 36, such reel having pivotally mounted and hung thereon a series of trays 37 upon which the articles to be baked are arranged, 40 5 designates the oven door, being pivotally mounted on one of the intermediate sections 12 upon a suitable pin or bolt 41, a suitable handle 42 being provided whereby the door may be swung outwardly from the oven.

10 Arranged to conform to the shape of the interior of the oven is a curved plate 44 which extends from end to end of the oven and from a point immediately inside and over the door to the top of the oven, which 15 plate is spaced apart from the inner sheet 31 of the curved section of the oven thereby leaving a space indicated at 45 forming a vent which connects with a stack manifold 46 by means of a series of open pipes or nipples 47, such stack-manifold 46 being in open communication with the stack 48. The lower end or mouth of the vent 45 is closed at all times except when the oven door is open. This is accomplished by means 20 25 of a flap damper 50 pivotally mounted on the oven wall at 51 and held in closed or full line position as shown in Fig. 3 by the upper plate 52 of the door 40. When the door is swung upwardly the plate 52 moves away 30 from the damper 50 and permits the same to fall into the dotted line position shown in Fig. 3 thereby opening the vent as herein-after more fully described.

The oven is provided with a series of flues 35 55, the passage of heat therethrough being regulated by a sliding damper 56 having openings 57 therein registering with the flues 55, the damper being operated by a worm 58 operating in a block 59, the worm 40 being provided with a suitable operating handle indicated at 60. The damper 56 is also provided with large openings 61 which extend over the pipes 47, such openings 61 being large enough so that the pipes 47 are 45 always in full open position, the damper being solely for the regulation of the flues 55 which control or regulate the passage of heat from the oven during the baking operation.

50 The reel is driven by means of a gear wheel 62 secured to the shaft 35, such gear wheel being driven by means of a worm 63 on a shaft 64, such shaft being provided with a gear 65 which is driven from a pinion 66 55 on the motor shaft 67 of a motor 68. One end of the shaft 64 is squared as indicated at 69 to receive a wheel or crank 70 by means of which the reel may be operated manually when desired.

60 The construction of the reel and the trays thereon it is understood may be of any well known form, but I have found that by curving the plate 20 as shown that the heat radiated from such curved plate is in upwardly diverging rays, the heat therefrom

being radiated upwardly along the sides of the oven as well as directly upward, the direct heat from the combustion chamber passing upwardly at each side of the plate as heretofore referred to.

70 When it is desired to open the oven, the oven door is swung outwardly on its hinge 41 by means of the handle 42 and the flap damper 50 drops downwardly into the dotted line position shown in Fig. 3 thereby 75 opening the vent 45, which being in open communication with the stack draws the heat from about the door upwardly through the vent and at the same time causes a slight inflow of air through the door instead of the 80 hot blast going outwardly as is commonly the case. This permits the operator to load and unload the oven in much shorter time and with much less danger than with ovens as ordinarily constructed.

85 I have also found that by arranging means described above for manually operating the driving mechanism that the operation of loading and unloading is greatly facilitated as the reel may be turned any desired distance by hand and stopped where desired. This feature of manual operation is also desirable where the power fails during the baking operation, as in such case the entire contents of the oven are frequently burned or 90 ruined before the same can be removed.

95 Should the contents of any tray become dislodged and fall in the oven, the plate 20 may be dropped by operating the latch 23 heretofore referred to, thereby permitting 100 the material to fall to the bottom of the combustion chamber and be removed through the door 16. The plate 20 may be reset and held in place by the latch 23.

105 We claim as our invention:—

1. An oven having a baking chamber, a door for the baking chamber, a stack for said oven, flues for regulating the passage of heat from the baking chamber to said stack, a vent in open communication at one end with 110 the stack and terminating at its other end within said baking chamber inside the door, and means whereby said vent is opened coincident with opening the door.

2. A reel oven comprising a baking chamber, a reel in said chamber, a door for said chamber extending across one side of said oven, a stack for said oven, a series of flues for said chamber communicating with said stack, means for regulating the passage of 115 heat from said chamber to said stack through the flues, a vent formed in the baking chamber having one end in open communication with said stack and having its mouth disposed within the baking 120 chamber along the top of the door opening, a damper pivotally mounted on the oven wall for the mouth of said vent, and means on said door arranged to engage and close said damper when the door is in closed position. 125

3. A reel oven comprising a baking chamber, a reel in the baking chamber, a stack, flues connecting the stack with the baking chamber, a curved plate between the baking chamber and the combustion chamber, means for pivotally mounting said plate along one side thereof, latch means for supporting the other side of said plate, said plate having openings along each side for the passage of 10 heat from the combustion chamber to the baking chamber, and a door for said combustion chamber.

4. A reel oven comprising a baking chamber, a combustion chamber arranged below the baking chamber, a reel in the baking chamber, means for revolving said reel, a door for said baking chamber in the side thereof, a stack, a manifold for said stack, a series of flues connecting said baking 20 chamber with said manifold, a damper arranged to regulate the passage of heat through said flues, a plate spaced apart from the inside of said baking chamber and extending throughout the length of the 25 baking chamber forming a vent having its lower end or mouth terminating at the top of said door inside the baking chamber, and a flap damper pivotally mounted at the mouth of said vent arranged to be engaged by said door when in closed position to close 30 said damper and to be disengaged by said door when in open position to open the mouth of said vent.

5. A reel oven comprising a baking chamber, a reel in said chamber, a door for said chamber extending across one side of said

oven, a stack for said oven, a stack manifold communicating with said stack, a plate spaced apart from the inner face of said chamber extending throughout the length of 40 said chamber forming a vent open at its lower end inside said chamber above the door and closed at its upper end, a series of nipples connecting said vent with said manifold, a series of flues extending through said 45 vent communicating with said chamber and said manifold, and a sliding damper in said manifold having openings therein registering with said nipples and said flues.

6. A reel oven comprising a baking chamber, a reel in said chamber, a door for said chamber extending across one side of said oven, a stack for said oven, a stack manifold communicating with said stack, a plate spaced apart from the inner face of said 50 chamber extending throughout the length of said chamber forming a vent open at its lower end inside said chamber above the door and closed at its upper end, a series of nipples connecting said vent with said 55 manifold, a series of flues extending through said vent communicating with said chamber and said manifold, and a flap damper pivotally mounted at the mouth of said vent arranged to be engaged by said door when 60 in closed position to close the lower end of said vent.

In testimony whereof we have hereunto set our hands and seals at Los Angeles, California, this 27th day of May, 1919.

JAMES DALTON.

BERNARD C. DE MEULLE.
